(57) **CLAIM**

The ornamental design for a water dispenser as shown and described.

DESCRIPTION

The patent or application file contains at least one drawing executed in color. Copies of this patent or patent application publication with color drawing(s) will be provided by the Office upon request and payment of the necessary fee.

1. Water dispenser

1.1 : Perspective

1.2 : Front

1.3 : Back

1.4 : Top

1.5 : Bottom

1.6 : Left

1.7 : Right

The colours of the product as appear in the visual description form no part of the design.

The thin coils shown on the back of the water dispenser form no part of the claimed design. The colours of the product as appear in the visual description form no part of the claimed design.

**1 Claim, 7 Drawing Sheets
